UNITED STATES PATENT OFFICE.

IRA L. SCOTT, OF FORT COLLINS, COLORADO, ASSIGNOR TO THE TWO WAY TRACTOR COMPANY, OF DENVER, COLORADO, A CORPORATION OF COLORADO.

TWO-WAY MOTOR-PLOW.

1,249,523.

Specification of Letters Patent. Patented Dec. 11, 1917.

Application filed May 18, 1916, Serial No. 98,425. Renewed May 2, 1917. Serial No. 166,049.

To all whom it may concern:

Be it known that I, IRA L. SCOTT, a citizen of the United States, residing at Fort Collins, in the county of Larimer and State of Colorado, have invented certain new and useful Improvements in Two-Way Motor-Plows; and I do declare the following to be a full, clear, and exact description of the invention, such as will enable others skilled in the art to which it appertains to make and use the same.

This invention relates to new and useful improvements in plows of that class having a motor driven frame provided with two sets of plows facing each other and movable into and out of their operative positions, so that the machine may be driven either forwardly or backwardly for plowing successive furrows without turning the machine entirely around.

The primary object of my invention is to provide a simple, practical and efficient tractor plow having a plow carrying member so mounted that a more direct pull upon the plows is obtainable than with any of the tractors in use at the present day.

Another object of this invention is to provide a device of this character which is so arranged that the traction wheel and steering members will travel on the solid ground, while the plows are in operation.

A still further object of the invention is to provide means for transversely adjusting and varying the number of plows carried by the balanced supplemental frame, and also making the plows easily removable therefrom.

A further object of the invention is to provide a device of this character which is simple and durable in construction, inexpensive to manufacture, and one which will be very efficient in operation.

With these and numerous other objects in view, my invention consists of the novel features of construction, combination and arrangement of parts which will be herein-after referred to and more particularly pointed out in the specification and claims.

In the accompanying drawings:

Figure 1 is a side elevation of my improved plow; and

Fig. 2 is a top plan view of the same.

In describing my invention, I shall refer to the drawings in which similar reference characters designate corresponding parts throughout the several views, and in which

the numeral 1 designates a main frame, having longitudinally extending side bars 2 and ends 3. Mounted between the side bars 2 of the frame 1 is a longitudinally extending bar 4, which projects from one end of the frame to the other. The side bars and ends of this frame, as well as the intermediate longitudinally extending bar 4, are secured at their ends by means of plates 5, which are riveted thereto as clearly shown in Fig. 2 of the drawings.

The longitudinally extending bar 4 between the side bars 2 of the frame is positioned nearer one of the side bars than the other, and over the narrowest space formed thereby is adapted to be mounted any type of engine of standard make, together with a means connected therewith for driving a transversely extending central shaft 6 which is mounted thereon in bearings on the opposite side bars of the main frame. A tractor wheel 7 is mounted on said shaft. The tractor wheel 7 is provided on its periphery with a plurality of transversely extending T iron cross bars which enable the same to readily grip into the ground.

The tractor wheel 7 forms a support for one side of the main frame 1, and the other side thereof is supported by a pair of steering and supporting wheels 8 which are disposed adjacent the ends of the same, and are mounted on axles 9, which project inwardly and upwardly through the opposite corners of the frame, and have a large beveled gear 10 on the upper end of the same. Projecting longitudinally with the frame 1, and spaced above the same, in bearings 11, which are secured to the bar 4, is a steering shaft 12 which is operated by a wheel 13, and has on its opposite ends beveled pinions which are adapted to mesh with the beveled gears 10 on the ends of the axles of the steering wheels. By this means it will be obvious that upon rotation of the wheel 13, the shaft 12 will be turned, and this motion will be transmitted to the steering supporting wheels 8, whereby the machine may be turned when desired.

The plows of this device are supported by means of a supplemental longitudinally extending balanced frame 15, which is pivotally mounted intermediate its ends on a pair of stub axles 16 which project inwardly from the side of the bar 4, and the adjacent side bar 2 beneath the axle or supporting shaft 6 of the tractor wheel 7. This frame

15 is substantially rectangular in shape, comprising parallel side bars 17, and ends 18. The supplemental frame 15 is provided adjacent its ends 18 with a pair of cross bars 19, which are disposed adjacent the opposite ends of the tractor wheel when the frame is in position, and which are adapted to form supports for longitudinally extending bars 20 which extend from said cross bars to the ends 18 of the frame, and form a support and securing means for the plows 21.

10 The longitudinally extending bars 20 are adapted to be transversely adjusted along 15 the ends 18, and the cross bars 19 between the sides 17 of the supplemental frame, by any desired means, preferably by means of bolts 22 projecting through the ends of the longitudinally extending bars, and openings 24 adapted for alinement therewith in the cross bars 19 and the ends 18. By this means, the plows 21 which are adapted to be removably secured to the longitudinally extending bars 20 may be adapted to various 25 positions, and by removing the plows and substituting smaller ones, the number may be increased accordingly.

15 The supplemental frame 15 supporting at its opposite ends the plows 21, is evenly balanced on the stub axles 16 beneath the axle of the tractor wheel, so that the same is adapted to easily swing or see-saw, so that the plows at either end may be brought into operative position. These plows 21 are facing each other, so that it will be obvious that when the machine is running in one direction, the plows at the rear of the supplemental frame when brought into contact with the ground, may be readily placed in 40 operation. Thus when the machine has reached one end of the field, it is not necessary to turn the same entirely around, but the supplemental frame is merely shifted, whereupon the plows at the opposite end of 45 the same are brought into operation, and the ones at its front end removed from the ground, whereby it may proceed back across the field. This supplemental frame is so mounted that only the plows at one end of 50 the same may be in operation at the same time.

15 The plows 21 are suspended from the bars 20 by supporting members 25, and additionally supported by braces 26. It will be obvious from the drawings that the plows which are shown two in number at each end of the supplemental frame, are spaced one in front of the other, and the plow nearest the tractor wheel is so positioned, however, that 60 it will always be in direct alinement with the adjacent plow. By this positioning, the machine will always plow evenly when in operation. Any type of engine may be used

to drive this plow, and the same may be mounted on the main frame adjacent one side of the tractor wheel, so that it may be easily connected with the axle 6 of the same. This axle extends across the top of the main frame, and is mounted in bearings 27 disposed on the side bars 2, and the intermediate bar 4.

10 From the foregoing description of the construction and operation of my improved motor plow, it will be seen that I have provided an extremely simple and efficient device of 75 this character for carrying out the objects of the invention.

I claim:

1. A device of the character described comprising a main frame, a tractor wheel 80 mounted in said frame, a supplemental balanced frame pivoted in the main frame beneath the axle of the tractor wheel and surrounding said wheel, and earth working elements on the ends of said supplemental frame disposed in the line of travel of the tractor wheel.

2. A device of the character described comprising in combination a main frame, a pair of supporting and guiding wheels at 90 one side of said frame, a transversely extending axle mounted therein intermediate its ends, a tractor wheel on said axle adjacent the opposite side of the frame, a longitudinally extending balanced supplemental 95 frame pivotally mounted in the main frame beneath the axle of the tractor wheel and surrounding said wheel, earthworking elements adjacent said wheel at the opposite ends of the supplemental frame and in the 100 path of the tractor wheel, and means to propel said tractor wheel.

3. A device of the class described comprising a main frame having a longitudinally extending bar adjacent one side, a pair of supporting and guiding wheels at the opposite sides of said frame, a transversely extending axle in said frame intermediate its ends, a tractor wheel on said axle between the longitudinally extending bar on the adjacent side of the frame, a longitudinally extending balanced supplemental frame pivotally mounted between the bar and adjacent side beneath the tractor axle, the ends of said supplemental frame being positioned 105 between the tractor wheel and the opposite ends of the main frame, and plows suspended from said ends of the supplemental frame.

110 In testimony whereof I have hereunto set 120 my hand in presence of two subscribing witnesses.

IRA L. SCOTT.
